UNITED STATES PATENT OFFICE.

ARTHUR HUTCHINSON CHASE AND HARRY LUTHER BOESCH, OF WASHINGTON, DISTRICT OF COLUMBIA, ASSIGNEES TO THE GOVERNMENT OF THE UNITED STATES.

FLASK FOR TORPEDOES.

1,354,091.

Specification of Letters Patent. Patented Sept. 28, 1920

Application filed March 22, 1919. Serial No. 284,471.

To all whom it may concern:

Be it known that we, ARTHUR H. CHASE and HARRY L. BOESCH, citizens of the United States, and residents of Washington, District of Columbia, have invented certain new and useful Improvements in Flasks for Torpedoes, of which the following is a specification.

Our invention relates generally to flasks 10 for torpedoes and more particularly to air flasks thereof.

Heretofore the flask of a torpedo has comprised a hollow steel cylinder of unitary structure which contained both the air flask 15 and water compartment. On the interior wall of the flask annular shoulders were provided and against ground joints on these shoulders flask heads were seated and bolted or otherwise mechanically secured in place. 20 These flask heads were removable and were usually domed outwardly.

The air flask is charged with compressed air under a high degree of pressure and the flask head of the after end is provided with 25 a suitable opening for connection to the outlet pipe. In all designs this flask head is subjected to more or less strain and serious difficulty has been experienced by reason of the compressed air leaking around this flask 30 head. This difficulty has taken a variety of forms but the most serious of these has been occasioned by the leaking compressed air building up pressure in the water compartment and this pressure eventually forces the 35 water into the combustion chamber. The effect is that of a "cold shot" which greatly interferes with the proper functioning of the power and control plant and in some instances completely paralyzes the entire 40 plant.

It is one of the objects of the present invention to provide the air flask of a torpedo with a flask head, in the after end thereof of such a nature as to eliminate any possibility 45 of leakage and at the same time provide in this flask head sufficient strength and rigidity to support any and all of the desired appurtenances.

Another object is to provide in connection 50 with a flask head such as outlined above a flask proper so constructed that the whole may be easily and cheaply manufactured by drawing, machining, or other approved mechanical process.

55 Another object is to provide a form of

construction of air flasks and heads which will result in a saving in the total weights of these parts.

Other objects and advantages will appear as the description proceeds and reference is 60 had to the accompanying drawings forming a part of this specification.

Figure 1 is a longitudinal section through the torpedo flask as assembled and Fig. 2 a longitudinal section on a larger scale showing in detail the water compartment and air flask structure as they appear just prior to assembling.

Referring to the drawings it will be seen that the flask of the torpedo comprises two 70 sections, the air flask 1 and the water compartment 2. Both the flask and the water compartment in their general structure are preferably of the usual hollow cylindrical form. The flask head 3 is formed integral 75 with the after end of the air flask and gradually increases in cross sectional area from a point near the wall of the air flask until it merges into this wall. It is domed outwardly and may be provided with an aperture as at 3' for the outlet pipe. By virtue of this integral construction, the flask head besides positively preventing any possibility of leakage possesses the requisite strength 80 and rigidity to support the fuel pot or like appurtenances. It is to be understood that the outlet pipe, fuel pot and like appurtenances form no part of the present invention but are referred to merely to better illustrate the capacity of the flask head 90 when constructed in accordance with the present invention.

Near the after end of the air flask its outer periphery is reduced and screw threaded and shoulders 4 and 5 are formed. The 95 shoulder 4 is provided with an annular recess 6 having its upper wall inclined as at 6'. The portion of the water compartment adjacent the air flask has its inner periphery correspondingly screw threaded and is also provided with shoulders as at 7 and 8. The shoulder 7 is formed with a flange 9 having an inclined wall 9' adapted to engage with the inclined wall 6' of the recess 6.

In assembling the flask, the water compartment is threaded upon the air flask so that the shoulders 4 and 5 abut respectively against the shoulders 7 and 8. The flange 9 then nests within the recess 6, the inclined walls of the flange and recess serving to 110

draw the parts together into their proper relation and thereby maintain the stream lines of the torpedo. The inclined walls of the flange add strength to the threaded part 5 and prevent the spreading of this part of the water compartment from the internal air pressure.

In order to seal the water compartment, one or more convolutions of the threads on 10 the internal screw threaded portion thereof are omitted and an annular groove is cut therein. The walls of this groove and the walls of the adjacent threads on the reduced portion of the air flask define a packing 15 chamber 10. This chamber 10 communicates with the exterior by means of one or more threaded apertures as at 11 and through these apertures lead packing 12 may be introduced and compressed and the apertures 20 are closed by suitable plugs. If desired, a lead gasket 13 may be interposed between the shoulders 5 and 8. In this manner the water compartment is effectively sealed.

In a design of torpedo in which the water 25 and fuel charges are carried otherwise than within a compartment formed within the air flask and sealed by the flask head retaining the air charge, the improved air flask with integral head may be employed for the purpose of reducing the weight of the flask the improved construction being much lighter in weight than the design of fixed or removable heads hitherto employed. Such saving in weight may be 30 utilized to permit an increase in the weight of explosive carried in the head of the torpedo, (the forward head, in such case, being made integral with the flask) or for the purpose of increasing the reserve buoyancy 35 of the torpedo, or for any other useful purpose which may be accomplished by a reduction in the weights of parts of the torpedo.

It is to be noted that a torpedo flask constructed in accordance with the present invention admits of practical and economical manufacture and at the same time provides the integral flask head with the advantages inherent therein, as above outlined, and preserves and maintains the strength of the 50 flask and the streamlike lines of the torpedo.

By way of illustration, the air flask with the flask head integral, as previously described may be manufactured by the drawing process well-known in the art. In this 55 manner the finished air flask and its integral after end flask head with the inherent advantageous properties, such as strength, rigidity, and the elimination of any possibility of leakage, are completed in a single 60 and comparatively inexpensive operation. This feature of the invention alone presents a very marked advance in the art, as the production of the air flask structures hitherto used, involved several expensive operations, one of the principal ones being ac-

curately machining the parts of difficult access on the interior of the flask. For instance, the machining of the shoulders and the ground joints thereon, on which the flask heads are seated, owing to their inaccessibility and the nicety and precision of the work required, made necessary the employment of trained and specially skilled workmen, the utilization of special tools and machinery and the expenditure of a considerable amount of time. Each of these factors are in themselves very expensive and tend to make the total expense involved enormous. Moreover the efficiency of the product in the most favorable instances 70 never even remotely approaches that attained by the present invention. 75

What we claim is:

1. An improvement in flasks for torpedoes comprising an air flask, a flask head formed integral with said air flask at its after end and a water compartment adapted to be secured to said air flask. 80

2. An improvement in flasks for torpedoes comprising an air flask having its outer periphery at its after end reduced and threaded, a flask head formed integral with said air flask at its after end and a water compartment having its inner periphery adjacent the air flask threaded for engagement with the reduced and threaded after end of the air flask. 90

3. An improvement in flasks for torpedoes comprising an air flask having its outer periphery at its after end reduced to form shoulders and the reduced portion threaded, a flask head formed integral with said air flask at its after end and a water compartment having shoulders adapted to abut against the shoulders of said air flask, the inner periphery of said water compartment being threaded for engagement with the reduced and threaded portion of the air flask. 100

4. An improvement in flasks for torpedoes comprising an air flask having its outer periphery at its after end reduced to form shoulders, the reduced portion thereof being threaded and one of said shoulders being provided with an annular recess having an inclined wall, and a water compartment having shoulders formed on its inner periphery adjacent the air flask, said inner periphery being threaded for engagement with the reduced and threaded portion of the air flask and one of said shoulders being provided with an annular flange having one of its walls inclined, the shoulders on the air flask and the water compartment being adapted to abut and the annular flange on the shoulder of the water compartment being adapted to nest within the annular recess of the shoulder of the air flask whereby the inclined wall of the flange and recess co-act to draw and hold the parts into their proper relation. 110

5. An improvement in flasks for torpedoes comprising an air flask having its outer periphery at its after end reduced and threaded, and a water compartment having
5 its inner periphery adjacent the air flask threaded for engagement with the reduced and threaded portion of the air flask, said threaded portion of the water compartment having one or more convolutions of its threads omitted and a groove formed there- 10 in, the wall of said groove with the walls of the threads of the air flask defining a packing chamber whereby said water compartment may be effectively sealed. 15

Signed at Washington, D. C. this 22nd 15
day of Jan., 1919.
